UNITED STATES PATENT OFFICE.

PETER ACKERMAN, OF BANGOR, MAINE.

IMPROVEMENT IN FIREMEN'S CAPS.

Specification forming part of Letters Patent No. 128,451, dated July 2, 1872.

To all whom it may concern:

Be it known that I, PETER ACKERMAN, of Bangor, in the county of Penobscot and State of Maine, have invented a new and useful Fireman's Cap; and I hereby declare the following to be a full, clear, and exact description thereof, which will enable others to make and use the same, reference being had to the accompanying drawing forming part of this specification—

Which shows a front view of my device at Figure 1, and at Fig. 2 its appearance when attached to a hat.

The object of my invention is to protect firemen against smoke and flame when entering a burning building for the purpose of saving life or property. The smoke in such cases is frequently so dense as to prevent access to goods or furniture, which have consequently to be abandoned. In order to overcome this I provide a hood of woolen or other suitable substance, which is drawn over the face and head. This keeps the smoke from the eyes and lungs, and yet permits sufficient air to pass through for breathing purposes. It is provided with eye-holes *c* covered with glass or isinglass, (preferably the latter, as being less liable to

accident from heat or breakage,) which enables the user to see his way.

In the drawing, *a* shows the hood, and *b b* the windows for the eyes. At *c* is a tape or elastic cord, by which it is secured beneath the chin when on. If desired, it may be fastened around the inside of a fire-hat, as shown in Fig. 2, and in this case, if an elastic is used at *c*, it will be sure to retain the hood in the top of the hat when not in use.

This device is capable of application to many other useful purposes by varying the material of which the hood is made. The seams are made flat, so as not to hurt the head when the hat is put on over the hood.

What I claim as my invention, and desire to secure by Letters Patent, is—

The protector, as described, consisting of the hood *a*, having isinglass windows for the eyes *b b*, and fastening beneath the chin, as set forth, either alone or in combination with a hat, as specified.

PETER ACKERMAN.
